Primary Examiner — Michelle E. Wilson*Assistant Examiner* — Richard E Yenchesky(74) *Attorney, Agent, or Firm* — Allen, Dyer, Doppelt + Gilchrist, P.A.(57) **CLAIM**

The ornamental design for a container device including bottom with contoured finger grips, as shown and described.

DESCRIPTION

FIG. 1 is a perspective view thereof;

FIG. 2 is a side view thereof;

FIG. 3 is a top view thereof;

FIG. 4 is a bottom view thereof; and,

FIG. 5 is a perspective bottom view thereof.

The broken lines shown illustrate environmental structure and form no part of the claimed design.
